(57) **ABSTRACT**

A system for an electronic payment card reader and a portable electronic device accessory includes an adapter assembly with a planar surface portion and an elongated rail portion extending from the planar surface portion. The elongated rail portion is removably couplable with the portable electronic device accessory. The adapter assembly includes a depressed portion with a first side and second side extending parallel with the first side. The first and second sides are removably couplable with first and second sides of the electronic payment card reader. Other aspects are described in the claims, drawings, and text forming a part of the present disclosure.

ABSTRACT

A system for an electronic payment card reader and a portable electronic device accessory includes an adapter assembly with a planar surface portion and an elongated rail portion extending from the planar surface portion. The elongated rail portion is removably couplable with the portable electronic device accessory. The adapter assembly includes a depressed portion with a first side and second side extending parallel with the first side. The first and second sides are removably couplable with first and second sides of the electronic payment card reader. Other aspects are described in the claims, drawings, and text forming a part of the present disclosure.

SYSTEM**

SUMMARY

A system is for an electronic payment card reader and a portable electronic device accessory that has at least one elongated channel portion. The system includes (I) an adapter assembly including (A) at least one planar surface portion, (B) at least one elongated rail portion extending from the at least one planar surface portion, wherein the at least one elongated rail portion is removably couplable with the portable electronic device accessory, and (C) a depressed portion having a first side, a second side, a third side, and a fourth side, wherein the second side extends parallel with the first side, wherein the third side extends perpendicular with the first side, wherein the fourth side extends perpendicular with the first side, wherein the first side of the depressed portion is removably couplable with a first side of the electronic payment card reader, and wherein the second side of the depressed portion is removably couplable with a second side of the electronic payment card reader.

In implementations the first side of the depressed portion of the adapter assembly includes a first component member having a side portion, wherein the first side of the depressed portion of the adapter assembly includes a second component member having a side portion, wherein the side portion of the first component member of the first side of the depressed portion of the adapter assembly contacts a first portion of the first side of the electronic payment card reader when the adapter assembly is coupled with the electronic payment card reader, and wherein the side portion of the first component member of the second side of the depressed portion of the adapter assembly contacts a second portion of the first side of the electronic payment card reader when the adapter assembly is coupled with the electronic payment card reader.

In implementations the first component member of the first side of the depressed portion of the adapter assembly is positioned adjacent to the second component member of the first side of the depressed portion of the adapter assembly.

In implementations the second side of the depressed portion of the adapter assembly includes a first component member having a side portion, wherein the second side of the depressed portion of the adapter assembly includes a second component member having a side portion, wherein the side portion of the first component member of the second side of the depressed portion of the adapter assembly contacts a first portion of the second side of the electronic payment card reader when the adapter assembly is coupled with the electronic payment card reader, and wherein the side portion of the second component member of the second side of the depressed portion of the adapter assembly contacts a second portion of the second side of the electronic payment card reader when the adapter assembly is coupled with the electronic payment card reader.

In implementations the first component member of the second side of the depressed portion of the adapter assembly is positioned adjacent to the second component member of the second side of the depressed portion of the adapter assembly.

In implementations the depressed portion of the adapter assembly is removably couplable with the electronic payment card reader in more than one orientation of the electronic payment card reader.

A system for a portable electronic device, a portable electronic device case, and an electronic payment card reader includes (I) an accessory assembly including (A) a first side portion including an exterior surface portion with at least one elongated channel portion therein, and (B) a second side portion extending perpendicular with the first side portion, wherein the accessory assembly is removably couplable to the portable electronic device case and is removably couplable to the portable electronic device, 10 wherein the accessory assembly includes at least one electronic function for the portable electronic device, wherein the first side portion of the accessory assembly remains unobstructed when the accessory assembly is coupled with the portable electronic device; and (II) an adapter assembly 15 including (A) at least one planar surface portion, (B) at least one elongated rail portion extending from the at least one planar surface portion, (C) a depressed portion having a first side, a second side, a third side, and a fourth side, wherein the second side of the depressed portion 20 extends parallel with the first side, wherein the third side of the depressed portion extends perpendicular with the first side, wherein the fourth side of the depressed portion extends perpendicular with the first side, wherein the depressed portion of the adapter assembly is removably couplable with the electronic payment card reader, and wherein the at least one elongated rail portion of the adapter assembly is sized to removably couple with the at least one elongated channel portion of the accessory assembly to 25 removably couple the adapter assembly with the accessory assembly.

In implementations the first side of the depressed portion is removably couplable with a first side of the electronic payment card reader, and wherein the second side of the depressed portion is removably couplable with a second side of the electronic payment card reader.

In implementations the first side of the depressed portion of the adapter assembly includes a first component member having a side portion, wherein the first side of the depressed portion of the adapter assembly includes a second component member having a side portion, wherein the side portion of the first component member of the first side of the depressed portion of the adapter assembly contacts a first portion of the first side of the electronic payment card reader when the adapter assembly is coupled with the electronic payment card reader, and wherein the side portion of the first component member of the second side of the depressed portion of the adapter assembly contacts a second portion of the first side of the electronic payment card reader when the adapter assembly is coupled with the electronic payment card reader.

In implementations the first component member of the first side of the depressed portion of the adapter assembly is positioned adjacent to the second component member of the first side of the depressed portion of the adapter assembly.

In implementations the second side of the depressed portion of the adapter assembly includes a first component member having a side portion, wherein the second side of the depressed portion of the adapter assembly includes a second component member having a side portion, wherein the side portion of the first component member of the second side of the depressed portion of the adapter assembly contacts a first portion of the second side of the electronic payment card reader when the adapter assembly is coupled with the electronic payment card reader, and wherein the side portion of the second component member of the second side of the depressed portion of the adapter assembly contacts a second portion of the second side of the electronic payment card reader.

payment card reader when the adapter assembly is coupled with the electronic payment card reader.

In implementations the first component member of the second side of the depressed portion of the adapter assembly is positioned adjacent to the second component member of the second side of the depressed portion of the adapter assembly.

In implementations the planar surface portion of the adapter assembly is adjacent the exterior surface portion of the first side of the accessory assembly when the at least one elongated rail portion of the adapter assembly is coupled with the at least one elongated channel portion of the accessory assembly.

In implementations the depressed portion of the adapter assembly is removably couplable with the electronic payment card reader in more than one orientation of the electronic payment card reader.

In implementations the at least one elongated channel of the accessory assembly lacks an end wall to provide at least one entry portion.

In implementations the accessory assembly further includes a cover component, wherein the cover component includes a planar surface portion, wherein the cover component includes at least one elongated rail portion extending from the planar surface portion, wherein the at least one elongated rail portion is sized to couple with the at least one elongated channel portion, and wherein the planar surface portion of the cover component is adjacent the exterior surface portion of the first side when the at least one elongated rail portion is coupled with the at least one elongated channel portion.

A system for a portable electronic device, an accessory assembly, and an electronic card reader includes (I) a portable electronic device case assembly including (A) an accessory docking bay for removably coupling with the accessory assembly, and (B) a device docking bay for removably coupling with the portable electronic device; and (II) an adapter assembly including (A) at least one planar surface portion, (B) at least one elongated one elongated rail portion extending from the at least one planar surface portion for coupling with the accessory assembly, and (C) a depressed portion having a first side, a second side, a third side, and a fourth side, wherein the second side of the depressed portion extends parallel with the first side, wherein the third side of the depressed portion extends perpendicular with the first side, wherein the fourth side of the depressed portion extends perpendicular with the first side, wherein the first side of the depressed portion is removably couplable with a first side of the electronic payment card reader, and wherein the second side of the depressed portion is removably couplable with a second side of the electronic payment card reader.

In implementations the first side of the depressed portion of the adapter assembly includes a first component member having a side portion, wherein the first side of the depressed portion of the adapter assembly includes a second component member having a side portion, wherein the side portion of the first component member of the first side of the depressed portion of the adapter assembly contacts a first portion of the first side of the electronic payment card reader when the adapter assembly is coupled with the electronic payment card reader, and wherein the side portion of the first component member of the second side of the depressed portion of the adapter assembly contacts a second portion of the first side of the electronic payment card reader when the adapter assembly is coupled with the electronic payment card reader.

In implementations the first component member of the first side of the depressed portion of the adapter assembly is positioned adjacent to the second component member of the first side of the depressed portion of the adapter assembly.

In implementations the depressed portion of the adapter assembly is removably couplable with the electronic payment card reader in more than one orientation of the electronic payment card reader.

In addition to the foregoing, other aspects are described in the claims, drawings, and text forming a part of the disclosure set forth herein. Various other aspects are set forth and described in the teachings such as text (e.g., claims and/or detailed description) and/or drawings of the present disclosure. The foregoing is a summary and thus may contain simplifications, generalizations, inclusions, or omissions of detail; consequently, those skilled in the art will appreciate that the summary is illustrative only and is NOT intended to be in any way limiting. Other aspects, features, and advantages of the devices and/or processes and/or other subject matter described herein will become apparent in the teachings set forth herein.

BRIEF DESCRIPTION OF THE FIGURES

FIG. 1 is a top perspective view of an accessory assembly. FIG. 2 is a bottom perspective view of the accessory assembly of FIG. 1.

FIG. 3 is a rear elevational view of the accessory assembly of FIG. 1.

FIG. 4 is a front elevational view of the accessory assembly of FIG. 1.

FIG. 5 is a top perspective view of a case assembly uncoupled from the accessory assembly of FIG. 1.

FIG. 6 is an enlarged top perspective view of a portion of the case assembly of FIG. 5 uncoupled from the accessory assembly of FIG. 1.

FIG. 7 is a bottom perspective view of the case assembly of FIG. 5 uncoupled from the accessory assembly of FIG. 1.

FIG. 8 is a first bottom perspective view of the case assembly of FIG. 5 coupled with the accessory assembly of FIG. 1.

FIG. 9 is a second bottom perspective view of the case assembly of FIG. 5 coupled with the accessory assembly of FIG. 1.

FIG. 10 is a first top perspective view of the case assembly of FIG. 5 coupled with the accessory assembly of FIG. 1.

FIG. 11 is a second top perspective view of the case assembly of FIG. 5 coupled with the accessory assembly of FIG. 1.

FIG. 12 is a top plan view of the case assembly of FIG. 5 coupled with the accessory assembly of FIG. 1.

FIG. 13 is a side elevational view of the case assembly of FIG. 5 coupled with the accessory assembly of FIG. 1.

FIG. 14 is a first bottom perspective view of the case assembly of FIG. 5 coupled with a portable electronic device, which are both coupled with the accessory assembly of FIG. 1.

FIG. 15 is a partially exploded top perspective view of the accessory assembly of FIG. 1.

FIG. 16 is a partially exploded bottom perspective view of the accessory assembly of FIG. 1.

FIG. 17 is a top perspective view of an adapter assembly.

FIG. 18 is a bottom perspective view of the adapter assembly of FIG. 17.

FIG. 19 is a first top perspective view of a card reader assembly.

FIG. 20 is a second top perspective view of the card reader assembly of FIG. 19.

FIG. 21 is a first bottom perspective view of the card reader assembly of FIG. 19.

FIG. 22 is a second bottom perspective view of the card reader assembly of FIG. 19.

FIG. 23 is a top perspective view of the adapter assembly of FIG. 17 coupled with the accessory assembly of FIG. 1.

FIG. 24 is a first top perspective view of the card reader assembly of FIG. 19 coupled with the adapter assembly of FIG. 17.

FIG. 25 is a second top perspective view of the card reader assembly of FIG. 19 coupled with the adapter assembly of FIG. 17.

FIG. 26 is a top perspective view of the card reader assembly of FIG. 19 coupled with the adapter assembly of FIG. 17 coupled with the accessory assembly of FIG. 1.

FIG. 27 is an exploded side-elevational lengthwise view of the card reader assembly of FIG. 19 uncoupled from the adapter assembly of FIG. 17.

FIG. 28 is an exploded cross-sectional side-elevational lengthwise view of the card reader assembly of FIG. 19 uncoupled from the adapter assembly of FIG. 17.

FIG. 29 is an enlarged exploded cross-sectional side-elevational lengthwise view of the right side portion of FIG. 28 of the card reader assembly of FIG. 19 uncoupled from the adapter assembly of FIG. 17.

FIG. 30 is an enlarged exploded cross-sectional side-elevational lengthwise view of the left side portion of FIG. 28 of the card reader assembly of FIG. 19 uncoupled from the adapter assembly of FIG. 17.

FIG. 31 is an exploded side-elevational lengthwise view of the card reader assembly of FIG. 19 coupled with the adapter assembly of FIG. 17.

FIG. 32 is an exploded cross-sectional side-elevational lengthwise view of the card reader assembly of FIG. 19 coupled with the adapter assembly of FIG. 17.

FIG. 33 is an enlarged exploded cross-sectional side-elevational lengthwise view of the right side portion of FIG. 32 of the card reader assembly of FIG. 19 coupled with the adapter assembly of FIG. 17.

FIG. 34 is an enlarged exploded cross-sectional side-elevational lengthwise view of the left side portion of FIG. 32 of the card reader assembly of FIG. 19 coupled with the adapter assembly of FIG. 17.

FIG. 35 is an exploded side-elevational widthwise view of the card reader assembly of FIG. 19 uncoupled from the adapter assembly of FIG. 17.

FIG. 36 is an exploded cross-sectional side-elevational widthwise view of the card reader assembly of FIG. 19 uncoupled from the adapter assembly of FIG. 17.

FIG. 37 is an enlarged exploded cross-sectional side-elevational widthwise view of the right side portion of FIG. 36 of the card reader assembly of FIG. 19 uncoupled from the adapter assembly of FIG. 17.

FIG. 38 is an enlarged exploded cross-sectional side-elevational widthwise view of the left side portion of FIG. 36 of the card reader assembly of FIG. 19 uncoupled from the adapter assembly of FIG. 17.

FIG. 39 is an exploded side-elevational widthwise view of the card reader assembly of FIG. 19 coupled with the adapter assembly of FIG. 17.

FIG. 40 is an exploded cross-sectional side-elevational widthwise view of the card reader assembly of FIG. 19 coupled with the adapter assembly of FIG. 17.

FIG. 41 is an enlarged exploded cross-sectional side-elevational widthwise view of the right side portion of FIG. 40 of the card reader assembly of FIG. 19 coupled with the adapter assembly of FIG. 17.

FIG. 42 is an enlarged exploded cross-sectional side-elevational widthwise view of the left side portion of FIG. 40 of the card reader assembly of FIG. 19 coupled with the adapter assembly of FIG. 17.

For a more complete understanding of implementations, reference now is made to the following descriptions taken in connection with the accompanying drawings. The use of the same symbols in different drawings typically indicates similar or identical items, unless context dictates otherwise.

With reference now to the figures, shown are one or more examples of Enhanced Portable Electronic Device Case Accessory Engagement System, articles of manufacture, compositions of matter for same that may provide context, for instance, in introducing one or more processes and/or devices described herein.

DETAILED DESCRIPTION

In the following detailed description, reference is made to the accompanying drawings, which form a part hereof. In the drawings, similar symbols typically identify similar components, unless context dictates otherwise. The illustrative implementations described in the detailed description, drawings, and claims are not meant to be limiting. Other implementations may be utilized, and other changes may be made, without departing from the spirit or scope of the subject matter presented here.

Turning to FIG. 1, depicted therein is a top perspective view of an accessory assembly 10. Depicted implementation of accessory assembly 10 is shown to include cover component 12 and accessory component 14. Depicted implementation of accessory assembly 10 is shown to include side 10a, side 10b, side 10c, and side 10d. Depicted implementation of cover component 12 is shown to include side 12a, side 12b, side 12c, and side 12d. Depicted implementation of accessory component 14 is shown to include side 14a with interface 14a1, side 14b, side 14c, side 14d, base portion 14e, and extended portion 14f.

Turning to FIG. 2, depicted therein is a bottom perspective view of accessory assembly 10. Depicted implementation of accessory component 14 is shown to include interior face 14g with electrical coupler 14g1.

Turning to FIG. 3, depicted therein is a rear elevational view of accessory assembly 10.

Turning to FIG. 4, depicted therein is a front elevational view of accessory assembly 10.

Turning to FIG. 5, depicted therein is a top perspective view of case assembly 20 uncoupled from accessory assembly 10. Depicted implementation of case assembly 20 is shown to include side 20a, end 20b, side 20c, end 20d, upper portion 20e, and accessory docking bay 20f. Depicted implementation of accessory docking bay 20f is shown to include wall 20/1, wall 20/2, and wall 20/3 with engagement rail 20/3a.

Turning to FIG. 6, depicted therein is an enlarged top perspective view of a portion of case assembly 20 uncoupled from accessory assembly 10.

Turning to FIG. 7, depicted therein is a bottom perspective view of case assembly 20 uncoupled from accessory assembly 10. In implementations case assembly 20 includes device docking bay 20g.

Turning to FIG. 8, depicted therein is a first bottom perspective view of case assembly 20 coupled with accessory assembly 10.

Turning to FIG. 9, depicted therein is a second bottom perspective view of case assembly 20 coupled with accessory assembly 10.

Turning to FIG. 10, depicted therein is a first top perspective view of case assembly 20 coupled with accessory assembly 10.

Turning to FIG. 11, depicted therein is a second top perspective view of case assembly 20 coupled with accessory assembly 10.

Turning to FIG. 12, depicted therein is a top plan view of case assembly 20 coupled with accessory assembly 10.

Turning to FIG. 13, depicted therein is a side elevational view of case assembly 20 coupled with accessory assembly 10.

Turning to FIG. 14, depicted therein is a first bottom perspective view of case assembly 20 coupled with portable electronic device 30, which are both coupled with accessory assembly 10. Depicted implementation of portable electronic device 30 is shown to include display 30a.

Turning to FIG. 15, depicted therein is a partially exploded top perspective view of accessory assembly 10. Depicted implementation of accessory component 14 is shown to include exterior upper 14h with longitudinal channel 14h1 having channel entry 14h1a, and with longitudinal channel 14h2 having channel entry 14h2a.

Turning to FIG. 16, depicted therein is a partially exploded bottom perspective view of accessory assembly 10. Depicted implementation of base 12e is shown to include elongated rail portion 12e1 and elongated rail portion 12e2.

Turning to FIG. 17, depicted therein is a top perspective view of adapter assembly 40. Depicted implementation of adapter assembly 40 is shown to include side 40a, side 40b, side 40c, side 40d, upper face 40e, and depressed portion 42. Depicted implementation of depressed portion 42 is shown to include side 42a with side portion 42al, side 42b, side 42c, side 42d, and base 42e with electrical interface 42e1, coupling surface 42e2, and electrical interface 42e3.

Turning to FIG. 18, depicted therein is a bottom perspective view of adapter assembly 40. Depicted implementation of adapter assembly 40 is shown to include base 40f with engagement rail 40f1, engagement rail 40f2, and electrical interface 40f3.

Turning to FIG. 19, depicted therein is a first top perspective view of electronic payment card reader 50. Depicted implementation of electronic payment card reader 50 is shown to include side 50a with payment card slot 50al, side 50b, side 50c with payment card slot 50c1, side 50d, and upper face 50e.

Turning to FIG. 20, depicted therein is a second top perspective view of electronic payment card reader 50.

Turning to FIG. 21, depicted therein is a first bottom perspective view of electronic payment card reader 50. Depicted implementation of electronic payment card reader 50 is shown to include lower face 50f with coupling surface 50f1, and electrical interface 50f2.

Turning to FIG. 22, depicted therein is a second bottom perspective view of electronic payment card reader 50.

Turning to FIG. 23, depicted therein is a top perspective view of adapter assembly 40 coupled with accessory assembly 10.

Turning to FIG. 24, depicted therein is a first top perspective view of electronic payment card reader 50 coupled with adapter assembly 40.

Turning to FIG. 25, depicted therein is a second top perspective view of electronic payment card reader 50 coupled with adapter assembly 40.

Turning to FIG. 26, depicted therein is a top perspective view of electronic payment card reader 50 coupled with adapter assembly 40 coupled with accessory assembly 10.

Turning to FIG. 27, depicted therein is an exploded side-elevational lengthwise view of electronic payment card reader 50 uncoupled from adapter assembly 40.

Turning to FIG. 28, depicted therein is an exploded cross-sectional side-elevational lengthwise view of electronic payment card reader 50 uncoupled from adapter assembly 40. In implementations side 40a includes side portion 40al and side portion 40a2. In implementations side 40c includes side portion 40c1 and side portion 40c2. In implementations adapter assembly 40 includes component member 43, component member 44, component member 45, component member 46, component member 47, and component member 48.

Turning to FIG. 29, depicted therein is an enlarged exploded cross-sectional side-elevational lengthwise view of the right side portion of FIG. 28 of electronic payment card reader 50 uncoupled from adapter assembly 40. In implementations side 42a includes side portion 42al and side portion 42a2.

Turning to FIG. 30, depicted therein is an enlarged exploded cross-sectional side-elevational lengthwise view of the left side portion of FIG. 28 of electronic payment card reader 50 uncoupled from adapter assembly 40. In implementations side 42c includes side portion 42c1 and side portion 42c2.

Turning to FIG. 31, depicted therein is an exploded side-elevational lengthwise view of electronic payment card reader 50 coupled with adapter assembly 40.

Turning to FIG. 32, depicted therein is an exploded cross-sectional side-elevational lengthwise view of electronic payment card reader 50 coupled with adapter assembly 40.

Turning to FIG. 33, depicted therein is an enlarged exploded cross-sectional side-elevational lengthwise view of the right side portion of FIG. 32 of electronic payment card reader 50 coupled with adapter assembly 40.

Turning to FIG. 34, depicted therein is an enlarged exploded cross-sectional side-elevational lengthwise view of the left side portion of FIG. 32 of electronic payment card reader 50 coupled with adapter assembly 40.

Turning to FIG. 35, depicted therein is an exploded side-elevational widthwise view of electronic payment card reader 50 uncoupled from adapter assembly 40.

Turning to FIG. 36, depicted therein is an exploded cross-sectional side-elevational widthwise view of electronic payment card reader 50 uncoupled from adapter assembly 40.

Turning to FIG. 37, depicted therein is an enlarged exploded cross-sectional side-elevational widthwise view of the right side portion of FIG. 36 of electronic payment card reader 50 uncoupled from adapter assembly 40.

Turning to FIG. 38, depicted therein is an enlarged exploded cross-sectional side-elevational widthwise view of the left side portion of FIG. 36 of electronic payment card reader 50 uncoupled from adapter assembly 40.

Turning to FIG. 39, depicted therein is an exploded side-elevational widthwise view of electronic payment card reader 50 coupled with adapter assembly 40.

Turning to FIG. 40, depicted therein is an exploded cross-sectional side-elevational widthwise view of electronic payment card reader 50 coupled with adapter assembly 40.

Turning to FIG. 41, depicted therein is an enlarged exploded cross-sectional side-elevational widthwise view of the right side portion of FIG. 40 of electronic payment card reader 50 coupled with adapter assembly 40.

Turning to FIG. 42, depicted therein is an enlarged exploded cross-sectional side-elevational widthwise view of the left side portion of FIG. 40 of electronic payment card reader 50 coupled with adapter assembly 40.

While particular aspects of the present subject matter described herein have been shown and described, it will be apparent to those skilled in the art that, based upon the teachings herein, changes and modifications may be made without departing from the subject matter described herein and its broader aspects and, therefore, the appended claims are to encompass within their scope all such changes and modifications as are within the true spirit and scope of the subject matter described herein. It will be understood by those within the art that, in general, terms used herein, and especially in the appended claims (e.g., bodies of the appended claims) are generally intended as "open" terms (e.g., the term "including" should be interpreted as "including but not limited to," the term "having" should be interpreted as "having at least," the term "includes" should be interpreted as "includes but is not limited to," etc.). It will be further understood by those within the art that if a specific number of an introduced claim recitation is intended, such an intent will be explicitly recited in the claim, and in the absence of such recitation no such intent is present. For example, as an aid to understanding, the following appended claims may contain usage of the introductory phrases "at least one" and "one or more" to introduce claim recitations. However, the use of such phrases should not be construed to imply that the introduction of a claim recitation by the indefinite articles "a" or "an" limits any particular claim containing such introduced claim recitation to claims containing only one such recitation, even when the same claim includes the introductory phrases "one or more" or "at least one" and indefinite articles such as "a" or "an" (e.g., "a" and/or "an" should typically be interpreted to mean "at least one" or "one or more"); the same holds true for the use of definite articles used to introduce claim recitations. In addition, even if a specific number of an introduced claim recitation is explicitly recited, those skilled in the art will recognize that such recitation should typically be interpreted to mean at least the recited number (e.g., the bare recitation of "two recitations," without other modifiers, typically means at least two recitations, or two or more recitations). Furthermore, in those instances where a convention analogous to "at least one of A, B, and C, etc." is used, in general such a construction is intended in the sense one having skill in the art would understand the convention (e.g., "a system having at least one of A, B, and C" would include but not be limited to systems that have A alone, B alone, C alone, A and B together, A and C together, B and C together, and/or A, B, and C together, etc.). In those instances where a convention analogous to "at least one of A, B, or C, etc." is used, in general such a construction is intended in the sense one having skill in the art would understand the convention (e.g., "a system having at least one of A, B, or C" would include but not be limited to systems that have A alone, B alone, C alone, A and B together, A and C together, B and C together, and/or A, B, and C together, etc.). It will be further understood by those within the art that typically a disjunctive word

and/or phrase presenting two or more alternative terms, whether in the description, claims, or drawings, should be understood to contemplate the possibilities of including one of the terms, either of the terms, or both terms unless context dictates otherwise. For example, the phrase "A or B" will be typically understood to include the possibilities of "A" or "B" or "A and B."

With respect to the appended claims, those skilled in the art will appreciate that recited operations therein may generally be performed in any order. Also, although various operational flows are presented in a sequence(s), it should be understood that the various operations may be performed in other orders than those which are illustrated, or may be performed concurrently. Examples of such alternate orderings may include overlapping, interleaved, interrupted, reordered, incremental, preparatory, supplemental, simultaneous, reverse, or other variant orderings, unless context dictates otherwise. Furthermore, terms like "responsive to," "related to," or other past-tense adjectives are generally not intended to exclude such variants, unless context dictates otherwise.

What is claimed is:

1. A system for an electronic payment card reader and a portable electronic device accessory that includes at least one elongated channel portion, the system comprising:

(I) an adapter assembly including

(A) at least one planar surface portion,

(B) at least one elongated rail portion extending from the at least one planar surface portion, wherein the at least one elongated rail portion is removably couplable with the portable electronic device accessory, and

(C) a depressed portion having a first side, a second side, a third side, and a fourth side, wherein the second side extends parallel with the first side,

wherein the third side extends perpendicular with the first side, wherein the fourth side extends perpendicular with the first side,

wherein the first side of the depressed portion is removably couplable with a first side of the electronic payment card reader, and wherein the second side of the depressed portion is removably couplable with a second side of the electronic payment card reader.

2. The system of claim 1,

wherein the first side of the depressed portion of the adapter assembly includes a first component member having a side portion, wherein the first side of the depressed portion of the adapter assembly includes a second component member having a side portion, wherein the side portion of the first component member of the first side of the depressed portion of the adapter assembly contacts a first portion of the first side of the electronic payment card reader when the adapter assembly is coupled with the electronic payment card reader, and

wherein the side portion of the first component member of the second side of the depressed portion of the adapter assembly contacts a second portion of the first side of the electronic payment card reader when the adapter assembly is coupled with the electronic payment card reader.

11

3. The system of claim 2,
wherein the first component member of the first side of the depressed portion of the adapter assembly is positioned adjacent to the second component member of the first side of the depressed portion of the adapter assembly. 5
4. The system of claim 3,
wherein the second side of the depressed portion of the adapter assembly includes a first component member having a side portion,
wherein the second side of the depressed portion of the 10 adapter assembly includes a second component member having a side portion,
wherein the side portion of the first component member of the second side of the depressed portion of the adapter assembly contacts a first portion of the second side of the electronic payment card reader when the adapter assembly is coupled with the electronic payment card reader, and
wherein the side portion of the second component member of the second side of the depressed portion of the 15 adapter assembly contacts a second portion of the second side of the electronic payment card reader when the adapter assembly is coupled with the electronic payment card reader.
20
5. The system of claim 4,
wherein the first component member of the second side of the depressed portion of the adapter assembly is positioned adjacent to the second component member of the second side of the depressed portion of the adapter assembly.
25
6. The system of claim 1,
wherein the depressed portion of the adapter assembly is removably couplable with the electronic payment card reader in more than one orientation of the electronic payment card reader.
30
7. A system for a portable electronic device, a portable electronic device case, and an electronic payment card reader, the system comprising:
35
- (I) an accessory assembly including
  - (A) a first side portion including and an exterior surface portion with at least one elongated channel portion therein, and
  - (B) a second side portion extending perpendicular with the first side portion,
wherein the accessory assembly is removably couplable 40 to the portable electronic device case and is removably couplable to the portable electronic device,
wherein the accessory assembly includes at least one electronic function for the portable electronic device,
wherein the first side portion of the accessory assembly 45 remains unobstructed when the accessory assembly is coupled with the portable electronic device; and
  - (II) an adapter assembly including
  - (A) at least one planar surface portion,
(B) at least one elongated one elongated rail portion 50 extending from the at least one planar surface portion,
(C) a depressed portion having a first side, a second side, a third side, and a fourth side,
wherein the second side of the depressed portion extends parallel with the first side,
wherein the third side of the depressed portion extends perpendicular with the first side,
wherein the fourth side of the depressed portion extends 55 perpendicular with the first side,
wherein the depressed portion of the adapter assembly is removably couplable the electronic payment card reader, and
60

12

- wherein the at least one elongated rail portion of the adapter assembly is sized to removably couple with the at least one elongated channel portion of the accessory assembly to removably couple the adapter assembly with the accessory assembly.
65
8. The system of claim 7,
wherein the first side of the depressed portion is removably couplable with a first side of the electronic payment card reader, and
wherein the second side of the depressed portion is removably couplable with a second side of the electronic payment card reader.
70
9. The system of claim 7,
wherein the first side of the depressed portion of the adapter assembly includes a first component member having a side portion,
wherein the first side of the depressed portion of the adapter assembly includes a second component member having a side portion,
wherein the side portion of the first component member of the first side of the depressed portion of the adapter assembly contacts a first portion of the first side of the electronic payment card reader when the adapter assembly is coupled with the electronic payment card reader, and
wherein the side portion of the first component member of the second side of the depressed portion of the adapter assembly contacts a second portion of the first side of the electronic payment card reader when the adapter assembly is coupled with the electronic payment card reader.
75
10. The system of claim 9,
wherein the first component member of the first side of the depressed portion of the adapter assembly is positioned adjacent to the second component member of the first side of the depressed portion of the adapter assembly.
80
11. The system of claim 10,
wherein the second side of the depressed portion of the adapter assembly includes a first component member having a side portion,
wherein the second side of the depressed portion of the adapter assembly includes a second component member having a side portion,
wherein the side portion of the first component member of the second side of the depressed portion of the adapter assembly contacts a first portion of the second side of the electronic payment card reader when the adapter assembly is coupled with the electronic payment card reader, and
wherein the side portion of the second component member of the second side of the depressed portion of the adapter assembly contacts a second portion of the second side of the electronic payment card reader when the adapter assembly is coupled with the electronic payment card reader.
85
12. The system of claim 11,
wherein the first component member of the second side of the depressed portion of the adapter assembly is positioned adjacent to the second component member of the second side of the depressed portion of the adapter assembly.
90
13. The system of claim 7,
wherein the planar surface portion of the adapter assembly is adjacent the exterior surface portion of the first side of the accessory assembly when the at least one

13

elongated rail portion of the adapter assembly is coupled with the at least one elongated channel portion of the accessory assembly.

14. The system of claim 7, 5
wherein the depressed portion of the adapter assembly is removably couplable with the electronic payment card reader in more than one orientation of the electronic payment card reader.

15. The system of claim 7, 10
wherein the at least one elongated channel of the accessory assembly lacks an end wall to provide at least one entry portion.

16. The system of claim 7, 15
wherein the accessory assembly further includes a cover component,
wherein the cover component includes a planar surface portion,
wherein the cover component includes at least one elongated rail portion extending from the planar surface portion,
wherein the at least one elongated rail portion is sized to couple with the at least one elongated channel portion, and
wherein the planar surface portion of the cover component is adjacent the exterior surface portion of the first side when the at least one elongated rail portion is coupled with the at least one elongated channel portion. 25

17. A system for a portable electronic device, an accessory assembly, and an electronic card reader, the system comprising:

(I) a portable electronic device case assembly including
(A) an accessory docking bay for removably coupling with the accessory assembly, and
(B) a device docking bay for removably coupling with the portable electronic device; and
(II) an adapter assembly including
(A) at least one planar surface portion,
(B) at least one elongated one elongated rail portion extending from the at least one planar surface portion for coupling with the accessory assembly, and
(C) a depressed portion having a first side, a second side, 35
a third side, and a fourth side, 40

14

wherein the second side of the depressed portion extends parallel with the first side,
wherein the third side of the depressed portion extends perpendicular with the first side,
wherein the fourth side of the depressed portion extends perpendicular with the first side,
wherein the first side of the depressed portion is removably couplable with a first side of the electronic payment card reader, and
wherein the second side of the depressed portion is removably couplable with a second side of the electronic payment card reader.

18. The system of claim 17, 10
wherein the first side of the depressed portion of the adapter assembly includes a first component member having a side portion,
wherein the first side of the depressed portion of the adapter assembly includes a second component member having a side portion,
wherein the side portion of the first component member of the first side of the depressed portion of the adapter assembly contacts a first portion of the first side of the electronic payment card reader when the adapter assembly is coupled with the electronic payment card reader, and

wherein the side portion of the first component member of the second side of the depressed portion of the adapter assembly contacts a second portion of the first side of the electronic payment card reader when the adapter assembly is coupled with the electronic payment card reader.

19. The system of claim 18, 20
wherein the first component member of the first side of the depressed portion of the adapter assembly is positioned adjacent to the second component member of the first side of the depressed portion of the adapter assembly.

20. The system of claim 17, 30
wherein the depressed portion of the adapter assembly is removably couplable with the electronic payment card reader in more than one orientation of the electronic payment card reader.
